(57) **CLAIM**

The ornamental design for a charging connector for an automobile, as shown and described.

DESCRIPTION

FIG. 1 is a top-front-left perspective view of a first embodiment of a charging connector for an automobile showing our new design.

FIG. 2 is a top-front-right perspective view thereof.

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof;

FIG. 8 is a left side elevational view thereof;

FIG. 9 is a top-front-left perspective view of a second embodiment of a charging connector for an automobile showing our new design.

FIG. 10 is a top-front-right perspective view thereof.

FIG. 11 is a front elevational view thereof;

FIG. 12 is a rear elevational view thereof;

FIG. 13 is a top plan view thereof;

FIG. 14 is a bottom plan view thereof;

FIG. 15 is a right side elevational view thereof; and,

FIG. 16 is a left side elevational view thereof.

The broken lines shown in FIGS. 6 and 8 that define unshaded regions represent the bounds of the first embodiment; the broken lines form no part of the first embodiment.
